Term of patent 14 years

Int. Cl. D6—01

U.S. Cl. D33—7

FIG. 3

FIG. 4

FIG. 1 is a front perspective view of a communication desk in accordance with my new design.

FIG. 2 is an end view thereof;

FIG. 3 is a top plan view thereof; and

FIG. 4 is a rear elevational view thereof.

The essential features of my design are the full line portions which in turn are characterized by the configuration of the leg units in their association with the table top, all as best illustrated in FIGURE 4.

I claim:

The ornamental design for a communication desk, as shown and described.
